UNITED STATES PATENT OFFICE.

WILLIAM H. HUBBARD, JR., OF NEWARK, NEW JERSEY, ASSIGNEE TO THE OHIO & COLORADO SMELTING & REFINING CO., OF DENVER, COLORADO, A CORPORATION OF COLORADO.

COOLING ORES.

1,173,273.

Specification of Letters Patent.

Patented Feb. 29, 1916.

Original application filed November 30, 1912, Serial No. 734,315. Divided and this application filed December 30, 1914. Serial No. 879,664.

To all whom it may concern:

Be it known that I, WILLIAM H. HUBBARD, Jr., a citizen of the United States, residing in Newark, Essex county, State of New Jersey, have invented certain new and useful Improvements in Cooling Ores, of which the following (a division of my application, Serial No. 734,315, filed November 30, 1912,) is a specification.

10 The present invention relates to cooling ores, or the like, from metallurgical or other furnaces, such, for example, as the product of a pre-roasting furnace of the Godfrey or analogous type, which is to be further treated on Dwight and Lloyd machines or the like.

15 The object of the invention is to effect the cooling of the ore at the intermediate stage quickly and cheaply, at the same time avoiding the annoyance of dust and smoke and bringing the ore into good physical condition for handling easily and further roasting.

20 In accordance with the invention, the hot ore is distributed in a comparatively thin layer on a flat table, or a series of tables, and is rabbled during its movement between the places of charge and discharge to continually expose fresh surfaces of ore to a cooling medium or mediums. The cooling tables for supporting the ore in this way may have a variety of forms; they may be circular, linear or otherwise shaped, and may be arranged in tiers to form superposed 25 tables, if desired. So, also, the rabbles for rabbling the ore may take various forms, and may have various arrangements relatively to the cooling tables.

25 In the embodiment to which this divisional application is directed, a stationary table is employed in conjunction with rotating baffles, and this may be used either alone or associated with a rotating table having stationary baffles, and in either case 30 it is preferable that the movable elements shall move in such manner as to produce a movement of the ore on the table in a path different from the line of movement of the table or the rabbles, and also extended in 35 length so far as practicable.

40 In the preferred embodiment of the apparatus herein claimed, the table is substantially circular while the path of the ore on the table is along a substantially spiral

line, this being effected by rotating the rabbles over the stationary table or, if desired, also passing the ore to a rotating table provided with stationary rabbles, so that in either case the ore is periodically forced against rabbles which rabble it and simultaneously shift it on the table progressively toward the discharge outlet. In this way the ore is automatically discharged after being repeatedly rabbed to expose fresh surfaces to the cooling medium or mediums along the extended path across the table and yet within a compact space of operation.

45 The cooling medium may be a current of gas, such as air, moved over and in contact with the ore on the table or through it, and of such volume and temperature as to produce the necessary reduction in the temperature of the ore under the conditions prevailing. As an alternative method of cooling, heat from the ore may be transferred to a cooling medium, such as water, circulated in contact with the under side of the table by conduction through the table, or liquid may be sprinkled on the ore to abstract the heat of vaporization of the liquid from the ore. Furthermore, all, or any two of these cooling means, may be used together to effect the desired reduction in temperature of the ore during its passage from the place of charge to the place of discharge.

50 In the accompanying drawings, illustrating two modifications of apparatus constructed in accordance with the present invention, Figure 1 represents an elevation, partly in section and partly broken away, of the arrangement wherein the table is stationary while the rabbles are rotatable; Fig. 2 is a diagram of the movement of the ore on the table in Fig. 1; Fig. 3 is an elevation, partly in section and partly broken away, of an apparatus having two superimposed tables with means for sprinkling the ore with a cooling liquid while on one of the tables, and with means for circulating a cooling fluid through the interior of the lower table; Fig. 4 is a top plan view of the lower table of Fig. 3, illustrating diagrammatically the movement of the ore on that table.

55 Referring to Figs. 1 and 2 of the drawings, the columns 1 resting on a suitable

foundation 2 support the hood 3 over the stationary circular table 4. A vertical shaft 5 mounted in suitable bearings 6 is driven by the gearing 7 and carries the arm 8 provided with the rabbles 9. The rabbles 9 are arranged along substantially a diametrical line across the circular table, and are each set at such an angle to this line that when the driving shaft 5 is rotated the ore on the 10 table is carried along a substantially spiral path, indicated by the broken lines in Fig. 2. The hood 3 is provided with a stack 10 to conduct the dust and gases away from the apparatus. The charging ore conduit 11 15 may extend directly from a preheating furnace or from any other suitable place and charge the hot ore onto the table at a place near the outer periphery thereof. The discharge ore conduit 12 is fastened to the 20 under side of the table around its discharge opening 13 and leads to any desired place, as a storage bin or conveyer.

When the shaft 5 is rotated at the proper speed by the gearing 7 and the ore is being charged at the proper rate of feed on to the outer periphery of the stationary table 4 from the conduit 11 in Figs. 1 and 2, the rabbles 9 push the ore in a comparatively thin layer around the table and inwardly 30 thereon in a spiral path and finally into the central opening 13, from whence it passes through the discharge conduit 12 into a place arranged to use, store or convey the ore. In this period during which the ore 35 is moved from the charging conduit to the discharging conduit, the air is drawn from the outside around the edge of table 4 and over and in contact with the ore and into the stack 10, either by a natural draft 40 brought about by the hot gases and heated air, or by a suitable fan. In either case, the air moves freely without substantial confinement by the apparatus at any point, while the volume of the cooling air is regulated in any suitable way to bring about 45 the desired reduction of temperature of the ore in its movement on the table. The ore is caused to move along a substantially spiral path considerably longer than the distance 50 between the conduits, so that an extended cooling operation is secured in a comparatively compact apparatus. Furthermore, the ore is repeatedly rabbled so that by continually exposing fresh surfaces thereof to 55 contact with the cooling air, the ore is progressively and efficiently cooled throughout its mass.

The apparatus of Figs. 3 and 4 comprises a stationary upper table 4, as in Fig. 1, and 60 a rotatable lower table 41, the upper set of rabbles 9 being rotatable and the lower set 9' being stationary. The circular table 41 is fastened to the driving shaft 5 and is rotatable therewith, while the rabbles 9' are 65 stationary. The ore is charged on to the

outer periphery of the upper table, is discharged from a point near the center thereof to a point near the center of the lower table, and is discharged from the outer periphery by the outermost rabbles 9' into a conduit 12 70 located at the proper place to catch the ore falling from the table so that the ore is moved through a substantially spiral path on each of the tables. Currents of cooling air may be induced over or through the ore 75 on each of the tables, and in addition to the cooling effect of the current of air, water is sprinkled on the ore preferably at the places indicated diagrammatically in Fig. 4, just behind the rabbles in the direction of rotation of the table, where the ore has just been overturned. The sprinkling apparatus comprises a stationary pipe 20 closed at its ends and provided with a series of holes through which the water passes out into the freshly 80 exposed ore. This pipe 20 is bent around the driving shaft 5 and is connected to a supply pipe 21 which communicates with a source of water supply. On the lower table the ore is moved around and outwardly in 85 an extended path of substantially the form of a spiral, and is repeatedly rabbled and sprinkled by the cooling liquid to a degree sufficient to effect the desired reduction of temperature when combined with the additional cooling effect of the air current induced over the ore. In this way the heat of vaporization of the water is taken from the freshly exposed ore while the direction 90 of the current of air is against the movement of the ore, so that the coolest air meets the coolest ore at the periphery of the table. 95

In addition to the current of cooling air induced over the ore and the stationary water sprinkling system, heat is also abstracted from the ore by water circulated in the hollow interior 30 of the table and provision is made for drawing air through the ore bed. The circulating cooling water is supplied from a pipe 31 communicating 100 with a suitable source and with the hollow interior 32 of the driving shaft. Conduits 33 fixed in the hollow interior of the table communicate with the passage in the shaft and conduct the water near the outer periphery of the table from whence the water passes back to the discharge pipes 34, when it reaches the required level, and out through the stationary pan 35 and outlet 36. In this way heat is conducted from the 105 ore through the table to this circulating cooling water. The table is also provided with a plurality of radially arranged narrow inclosed passages 37 passing entirely through the table without permitting the 110 leakage of water from the hollow interior of the table for the purpose of passing air 115 through the ore on the table. The air currents, the sprinkling water and the circulating cooling water are regulated in amount 120 125 130

so as to effect in combination the desired reduction of temperature of the ore during its movement from the place of charge to the place of discharge.

5 Having thus described my invention, what I claim is:

1. In apparatus for cooling hot ore, or the like, the combination with a flat circular cooling table for supporting the ore in a comparatively thin layer, means for charging the ore onto the table, near its outer edge, means for discharging the ore from the table near its center, a rotatable shaft provided with rabbles for rabbling the ore on the table and for effecting movement of the ore from the place of charge to the place of discharge, means for rotating said shaft; and means for progressively cooling the ore on the table during its movement from the place of charge to the place of discharge; substantially as described.
2. In apparatus for cooling hot ore, or the like, the combination with a flat circular cooling table for supporting the ore in a comparatively thin layer, means for charging the ore on to the table at its outer edge, a rotating shaft passing through the center of said table, rabbles carried by said shaft and arranged for rabbling the ore on the table and for effecting movement of the ore spirally around said shaft from the place of charge to the place of discharge, means for rotating said shaft and means for progressively cooling the ore on the table during its movement from the place of charge to the place of discharge; substantially as described.
3. In apparatus for cooling hot ore, or the like, the combination with a flat circular cooling table for supporting the ore in a comparatively thin layer, means for charging the ore on to the table near the outer edge thereof, a rotatable member projecting through said table near its center and provided with rabbles for rabbling the ore on the table and for effecting movement of the ore along said table in a spiral course to the place of discharge, means for cooling said

ore during said movement, said table having an opening through the center into 50 which the progressively cooled ore may be pushed by the innermost rabbles, and means for circulating a cooling fluid over said ore during its progressive movement; substantially as described.

4. In apparatus for cooling hot ore, or the like, the combination with a flat circular cooling table for supporting the ore in a comparatively thin layer, means for charging the ore on to the table near the periphery 60 thereof, a rotatable member provided with rabbles set at an angle for effecting spiral movement of the ore from the place of charge toward the center of the table, means for rotating said member and means for 65 drawing cooling air around the edge of said table for progressively cooling the ore on the table during its movement from the place of charge toward the center of the table, said table having an opening near its 70 center into which the cooled ore is ultimately pushed; substantially as described.

5. In apparatus for cooling hot ore, or the like, the combination with a stationary cooling table for supporting the ore in a comparatively thin layer, said table having a discharge opening at its center; of means for charging the ore on to the table, a rotatable member projecting through said table and provided with rabbles for rabbling the 80 ore on the table and for effecting movement of the ore along the table in a spiral path from the place of charge to a place of discharge, means for water cooling said member, means for rotating said member, and 85 means for progressively cooling the ore on the table during its movement from the place of charge to the place of discharge; substantially as described.

In testimony whereof, I affix my signature, in presence of two witnesses.
